ICE TRAY

Michael K. Buchanan, Norfolk, Va.

Application April 23, 1946, Serial No. 664,380

7 Claims. (Cl. 62—108.5)

1

This invention relates to ice trays and more particularly to an improved construction of an ice tray having means for releasing the ice cubes from the pan and from the grid.

In my prior Patent 1,983,535, granted January 10, 1933, I have disclosed an ice tray comprising a pan and a grid provided with means for raising the grid in the pan to release the grid and the cubes, frozen thereto, from the pan. In the construction disclosed in that patent the grid is rigid and the cubes therefore remain bonded to the grid when the cubes and grid are released from the pan.

In Reissue Patent 18,819, granted on May 2, 1933, to Albert G. Horton and me, there is disclosed an improvement over my earlier patent in which the grid is made in two relatively movable parts and in which means are provided for raising one of the parts of the grid. This results not only in releasing the grid and the cubes from the pan but also in releasing the cubes from the grid.

The device of the present invention is an improvement over the devices of the two prior patents. In the development of ice trays, various means have been provided for releasing the cubes from the pan and the grid, such means usually including a grid consisting of relatively movable parts. In some of these devices the leverage obtainable is not sufficient for breaking the bond between the cubes and the pan and grid and in other devices the initial movement of a part of the grid is too abrupt resulting in shattering of the ice cubes.

In the present invention I have provided an improved construction for releasing the cubes from the pan and the grid in which a minimum of force is required and in which the cubes are released without shattering. In carrying out the invention I provide a pan of conventional construction and a grid member. The grid member consists of a pair of longitudinal members and a plurality of cross members or fins. An operating lever is secured to the longitudinal members adjacent each end and is provided with a toe or extension overlapping the upper edge of the pan. When the levers are swung on their pivots, the difference in the distance from the pivot to the point of connection to the two longitudinal members causes relative movement of the longitudinal members. A certain amount of lost motion is provided in the connections between the levers and the longitudinal members with the result that the initial movement of the levers causes an upward movement of the entire grid,

2

thus loosening the cubes from the bottom, side and end walls of the pan.

Further movement of the levers, after the lost motion has been taken up, causes upward movement of one of the longitudinal members with respect to the other and I therefore provide means for spreading or separating the longitudinal members when this relative movement occurs. The separation of the members moves the ice cubes outwardly or laterally and thus releases them from the longitudinal members and the cross members of the grid, freeing the cubes. Any suitable means may be employed for separating or spreading the longitudinal members.

One such means, herein illustrated, is to provide projections on the surface of one of the members and openings or depressions in the other members in which the projections are normally received. When the two members are moved relatively to each other to bring the projections out of alignment with the depressions or openings, the projections engage the surface of the second longitudinal member and cause the members to spread.

Such construction provides a tray from which ice cubes can be readily removed and in which the cubes are not shattered or broken when released.

In the accompanying drawing I have shown one form of the invention. In this showing:

Fig. 1 is a plan view;

Fig. 2 is a longitudinal, sectional view on line 2—2 of Fig. 1, showing the grid in lowered position within the pan for the freezing of cubes;

Fig. 3 is a transverse, vertical, sectional view on line 3—3 of Fig. 2;

Fig. 4 is a longitudinal, sectional view, similar to Fig. 2, showing the operating levers raised to a point where the entire grid has been moved upwardly in the pan to separate the cubes from the bottom, side and end walls of the pan;

Fig. 5 is a similar view showing further upward movement of the levers causing separation of the longitudinal members and release of the cubes from the grid;

Fig. 6 is a transverse, vertical, sectional view on line 6—6 of Fig. 5;

Fig. 7 is a similar view on line 7—7 of Fig. 5; and

Fig. 8 is a detailed, sectional view on line 8—8 of Fig. 1.

Referring to the drawing, the reference numeral 1 designates generally the pan which may be of any suitable size and shape. The pan is preferably formed of aluminum or an aluminum

alloy, although it may be formed of any other metal or of any material which is heat conductive. As shown, the pan is provided with side walls 2 and end walls 3 and 4. Either or both of the end walls may be curved as indicated at 5 to facilitate release of the cubes from the pan and the side walls may slant outwardly from bottom to top to further facilitate the release of the cubes. The juncture of the vertical walls and the bottom of the pan is preferably mounted as at 5.

Within the pan I provide a grid designated generally by the reference numeral 6'. As shown, the grid consists of a pair of longitudinal members 6 and 7 and a plurality of cross members or fins 8. The cross members may taper in thickness from the center to each end to facilitate the release of the cubes from the grid. The longitudinal member 7 is provided with a plurality of projections 38 on the side toward the longitudinal member 6. The longitudinal member 6 is provided with means for receiving these projections and permitting the two longitudinal members to be arranged in contact with each other as shown in Fig. 3. This means may consist of registering openings 9 or the material of the longitudinal members may be merely stamped to form a depression of the proper size to receive the projection 38. Each of the cross members is provided with a relatively wide slot 10 at the bottom and is further provided with a tapering slot 11' extending from a point just above the slot 10 to the upper edge and being of a width substantially equal to the thickness of the two cross members at the top. One of the longitudinal members, illustrated as the longitudinal member 6, is provided with a plurality of openings 11 equal in number to the number of cross members and these openings 11 are connected to the bottom edge of the longitudinal member by slots 12. Arranged to align with these openings are slots 13 formed in the lower edge of the longitudinal member 7. The upper edges of the longitudinal members are provided with spaced pairs of ears 14 to receive the upper edges of the cross members.

The grid is assembled by arranging the longitudinal members adjacent each other as shown in the drawings and then inserting the cross members so that the sections 15 between the bottom of the slot 11' of each cross member and the top of the slot 10 is passed through the slot 12 in one of the cross members and is arranged in the slot 13 in the other cross member. When this section 15 of the cross member enters the opening 11, the cross member is turned to a vertical or nearly vertical position and the upper edges are received between the pairs of ears 14.

The grid actuating means comprises a pair of levers 16, one being arranged at each end of the tray. These levers are provided with extensions 17 extending over the bead 28 formed on the edge of the pan and engaging this bead when the levers are actuated to serve as a fulcrum. The longitudinal member 6 is provided with a recess 18 adjacent each end and the longitudinal member 7 is provided with a similar recess 19, slightly spaced therefrom. The longitudinal member 6 is provided with an ear 20 in alignment with the recess 19 and the longitudinal member 7 is provided with an ear 21 adjacent the recess 18. The actuating levers are provided with slots 22 which straddle the ears 20 and 21 and between the two portions of the lever on the opposite sides of these slots, pins or bolts 23 and 24 extend. The pin or bolt 23 passes through an opening 25 in the ear

10

20 and the pin or bolt 24 passes through an opening 26 in the ear 21. The openings 25 and 26 are of greater diameter than the pins or bolts 23 and 24 so that upon initial upward movement of the levers from the position shown in Fig. 2 of the drawing to the position shown in Fig. 4 of the drawing, no relative movement occurs in the two longitudinal grid members but an upward movement of the entire grid as a whole takes place.

The operation of the device is as follows: The grid is placed in the pan with the bottom of the grid in engagement with the bottom of the pan. The bottom of the pan may be provided with several pairs of spaced projections 27, formed by stamping or otherwise, to receive the longitudinal members and properly position the grid in the pan. The grid is of course properly dimensioned and shaped to be received in the pan, that is, if one end wall of the pan is sloped as indicated at 4, the corresponding end of the grid is similarly shaped and the cross members are properly dimensioned to extend to each side wall 2 of the pan.

With the grid arranged in the pan in the position shown in Fig. 2 of the drawing, the tray is filled with water and placed in the freezing compartment of a refrigerator in the usual manner. After the water has been formed into ice cubes, the tray is removed from the refrigerator. To remove the cubes from the tray, the levers 16 are first moved upwardly from the position shown in Fig. 2 to the position shown in Fig. 4. This movement of the lever 16 causes the toes or extensions 17 to bear down on the beaded edge 28 of the pan and raise the grid, with the cubes attached to it from the position shown in Fig. 2 to the position shown in Fig. 4. The two longitudinal members 6 and 7 remain in close contact with each other with the projections 38 in the openings 9 because no relative movement takes place between these two members. The slight upward movement of the grid, however, is sufficient to free the cubes from the bottom, sides and end walls of the pan. As will be seen in Fig. 4 of the drawing, bolts or pins 23 and 24 have moved up into engagement with the tops of the openings 25 and 26 and further upward movement of the lever 16 causes relative movement of the longitudinal grid members 6 and 7 to the position indicated in Figs. 5 and 6 of the drawing. This is due to the fact that the pin 24 swings in a larger arc than the pin 23 causing greater relative movement of the longitudinal grid member 7 than the movement of the member 6.

The relative movement of the longitudinal members brings the projections 38 out of alignment with the openings 9 in the grid member 6. As the projections 38 engage the surface of the grid member 6, the lower edges of these members are spread, the movement of the upper edges of the members being limited by the width of the upper end of the slot 11'. This spreading of the lower edges of the grid members is sufficient to push the ice cubes outwardly or laterally and release them from the grid. The thus released cubes may either be dropped into the pan or taken out of the grid sections.

I claim:

1. An ice tray comprising a pan and a grid, the grid comprising a pair of longitudinal members arranged beside and in contact with each other and a plurality of cross members secured to the longitudinal members, a lever at each end of the grid, secured to each of the longitudinal members and having a portion adapted to engage

the adjacent edge of the pan to initially raise the grid in the pan when the levers are actuated, means for moving one of the longitudinal members upwardly with respect to the other upon further actuation of the levers, and means for spreading the lower edges of the longitudinal members upon upward movement of one of them with respect to the other.

2. An ice tray comprising a pan and a grid, the grid comprising a pair of longitudinal members arranged beside and in contact with each other and a plurality of cross members secured to the longitudinal members, a lever at each end of the grid having a fulcrum portion adapted to engage the edge of the pan to initially raise the grid in the pan when the levers are actuated, each of the levers being connected to the longitudinal members at different distances from the fulcrum portion whereby further movement of the levers causes relative movement of the longitudinal members, and means for spreading the lower edges of the longitudinal members from each other upon relative movement thereof.

3. An ice tray comprising a pan and a grid, the grid comprising a pair of longitudinal members and a plurality of cross members secured to the longitudinal members, a lever at each end of the grid having a fulcrum portion adapted to engage the edge of the pan to initially raise the grid in the pan when the levers are actuated, each of the levers being connected to the longitudinal members at different distances from the fulcrum portion whereby further movement of the levers causes relative movement of the longitudinal members, and projections formed on one of the longitudinal members, the other longitudinal member being shaped to receive the projections and permit the longitudinal members to be normally positioned in close contact with each other whereby relative movement of the longitudinal members causes spreading of the lower edges of the members.

4. An ice tray comprising a pan and a grid, the grid comprising a pair of longitudinal members arranged beside and in contact with each other and a plurality of cross members secured to the longitudinal members, a pair of levers, one at each end of the grid, connected to both of the longitudinal members and having a fulcrum portion to engage the edge of the pan to initially raise the grid in the pan upon actuation of the levers, lost motion connections between the levers and the longitudinal members whereby further movement of the levers causes relative movement of the longitudinal members, and means for spreading the lower edges of the longitudinal members upon relative movement of said members.

5. An ice tray comprising a pan and a grid, the grid comprising a pair of longitudinal members

and a plurality of cross members secured to the longitudinal members, a pair of levers, one at each end of the grid, connected to both of the longitudinal members and having a fulcrum portion to engage the edge of the pan to initially raise the grid in the pan upon actuation of the levers, lost motion connections between the levers and the longitudinal members whereby further movement of the levers causes relative movement of the longitudinal members, and projections formed on one of the longitudinal members, the other longitudinal member being shaped to receive the projections and permit the longitudinal members to be normally positioned in close contact with each other whereby relative movement of the longitudinal members causes spreading of the lower edges of the members.

6. An ice tray comprising a pan and a grid, the grid comprising a pair of longitudinal members normally arranged side by side and a plurality of transverse members, one of the longitudinal members being provided with projections and the other longitudinal member being shaped to receive said projections to permit the members to normally be positioned side by side, and means for moving the longitudinal members relatively to each other to bring the projections of one member out of alignment with the shaped portions of the other member and cause the lower edges of the longitudinal members to spread.

7. An ice tray comprising a pan and a grid, the grid comprising a pair of longitudinal members normally arranged side by side and a plurality of transverse members, one of the longitudinal members being provided with projections and the other longitudinal member being shaped to receive said projections to permit the members to normally be positioned side by side, a lever connected to each end of the grid and having a portion engaging the edge of the pan to raise the grid in the pan upon initial actuation of the levers, further movement of the levers causing relative movement of the longitudinal members to bring the projections of one of the members out of alignment with the shaped portions of the other member and spread the lower edges of the members.
